UNITED STATES PATENT OFFICE.

HENRI MAHEUX, OF MONTREAL, QUEBEC, CANADA.

MATCH-BOX.

1,392,429.

Specification of Letters Patent.

Patented Oct. 4, 1921.

Application filed October 12, 1920. Serial No. 416,495.

To all whom it may concern:

Be it known that I, HENRI MAHEUX, a subject of the King of Great Britain, residing at Montreal, Providence of Quebec, Canada, have invented certain new and useful Improvements in Match-Boxes; and I do hereby declare that the following is a full, clear, and exact description of the invention, such as will enable others skilled in the art 10 to which it appertains to make and use the same.

The present invention relates to new and useful improvements in cartons or boxes for containing matches, tooth picks or the like.

15 The primary object of the invention is the provision of a carton or box in which the said matches, tooth picks or the like can be dispensed and which is so constructed that the same may also be used for a container for said matches or from which they can be removed a few at a time.

Another object of the invention is the provision of a container having a plurality of closing flaps or sections, one of which may 25 be moved outwardly, when the device is used as a container, for the purpose of delivering matches or the like to the user a few at a time.

Still another object of the invention is 30 the provision of a carton or box of the type above specified which is used particularly for matches and which may have upon the sides thereof suitable abrasive substance upon which the matches can be lighted.

35 A further object of the invention is the provision of a carton or box such as described so constructed that the same will produce a tightly closed container in which matches, tooth picks and the like may be shipped or dispensed without danger of the 40 opening of the said box or carton and the consequent loss of its contents.

A still further object of the invention is 45 the provision of a carton or box such as above referred to, which will be comparatively simple and inexpensive to manufacture, reliable and efficient in use, and readily operated.

With the above and other objects in view, 50 the present invention resides in the novel features of construction, formations, combinations, and arrangements of parts to be hereinafter more fully described, claimed,

and illustrated in the accompanying drawings forming a part of the present application and in which:

Figure 1 is a perspective view of the invention used as a container for matches or the like;

Fig. 2 is a similar view of the same closed and illustrating its use for shipping or dispensing purposes;

Fig. 3 is a plan view of the blank from which the said carton or box is constructed;

Fig. 4 is a detail perspective view showing the closing sections or flaps in open position;

Fig. 5 is a vertical sectional view taken through Fig. 1; and,

Fig. 6 is an enlarged detail sectional view illustrating the supporting clip.

Referring now to the accompanying drawings by corresponding characters of reference throughout the several views, the numeral 7 designates in general my improved box or container which is of substantially rectangular formation, comprising a bottom 8 to the opposite longitudinal edges of which are connected the side members 9. A lower end member 10 is formed upon the lower edge of the bottom 8 and is adapted to be folded at right angles thereto, after which the lower end locking flaps 11 may be folded upon the outer side thereof and tacked thereto by a suitable fastener 12. 85 These lower end locking members 11 are formed upon the lower edges of the side members 9.

Upper end members 13 are formed upon the opposite edges of the side members 9 and are folded upon themselves as illustrated in Figs. 5 and 6 of the drawings. A movable end or supporting member 14 is formed upon the upper edge of the bottom 8 and is free to move relative to the end members 13. This member 14 likewise supports the upper flap 15 which is tapered at its free end slightly as shown at 16, and has secured to its opposite side edges upper side locking flaps 17 provided with inwardly 100 tapered extensions 18 which are adapted to engage the slits 19 formed in the side members 9 for locking this upper closing member in the position shown in Fig. 1 of the drawings.

The upper side locking flaps 17 have se-

cured thereto suitable abrasive sections or strips 20 upon which matches or the like may be struck if desired.

The lower end member 10 has hingedly connected and integrally formed upon its free edge a lower hinged closure 21 which is adapted when the device is used for dispensing or shipping matches or the like to extend beneath the tapered end 16 of the upper closing flap or section 15, as clearly illustrated in Fig. 2.

The lower closure 21 is provided with side flaps 22 which, when the device is assembled, project into the container in engagement with the inner surfaces of the side members

9. The edges of the members 22 are curved as at 23 in such manner that they will have sliding engagement with the lower end of the section 15, as shown in Fig. 1, and when the closing flap 21 is pulled outwardly, as shown in Fig. 1, these edges 23 will engage the lower edge of the flap 15 and limit the outward movement of the said closure 21.

As shown in Fig. 2 of the drawings, the device is used for the purposes of shipping or dispensing matches, tooth picks and other like articles. After the purchaser receives the carton or box 7, he may suspend the same from a suitable support by means of a hook 24 which is attached to the bottom 8 by bending the same as shown at 25 or in any other similar manner. He then disengages the lower closing flap or section 21 from the tapered end 16 of the upper section 15 and pulls the flap 21 outwardly, as shown in Figs. 1 and 5. As the device is then supported on end, the contents thereof will fall

into the chute which is provided by the section 21 and its side members 22 from where said contents can be removed a few at a time. 40

From the foregoing description taken in connection with the accompanying drawings, it will be manifest that a carton or box is provided for matches, tooth picks or similar articles, which will fulfil all of the necessary requirements of such a device, and it should be understood in this connection that various minor changes in the specific details of construction can be resorted to within the scope of the appended claims, without departing from the spirit or sacrificing any of the advantages of the invention. 50

Having thus fully described the invention, what I claim as new and desire to protect by Letters Patent is: 55

In a carton such as described, the combination of opposite side and end members and a bottom therefor, an upper closing section secured to one end of the box and having interlocking engagement with the sides of the box, the lower end of the said upper closing section being tapered, a lower closing section hinged to the lower end of the box, an extension thereon fitted beneath the lower tapered edge of the upper closing section, side members formed upon the lower closing section and fitted within the box, said lower section adapted to be pulled outwardly and with the side sections thereof to form a discharge chute for the contents of said box. 60 65 70

In witness whereof I have hereunto set my hand.

HENRI MAHEUX.
